DESIGN FOR A SERVING RACK OR THE LIKE

Anthony W. Planeta Rahway, N. J.

Application March 13, 1940, Serial No. 90,879

Term of patent 3½ years

To all whom it may concern:

Be it known that I, Anthony W. Planeta, a citizen of the United States, residing at Rahway, in the county of Union and State of New Jersey, have invented a new, original, and ornamental Design for a Serving Rack or the like, of which the following is a specification, reference being had to the accompanying drawing, forming part thereof.

ing rack or the like, showing my new design, and Figure 2 is a side elevational view thereof.

The dominant feature of the design resides in the handle portion of the serving rack or the like, shown in full lines.

I claim:

The ornamental design for a serving rack or the like, as shown and described.

ANTHONY W. PLANETA.
